UNITED STATES PATENT OFFICE.

JOHN C. HEBDEN, OF PROVIDENCE, RHODE ISLAND, AND FREDERICK H. DANIELL, OF FRANKLIN, NEW HAMPSHIRE; MARY B. DANIELL EXECUTRIX OF SAID FREDERICK H. DANIELL, DECEASED.

JACK-SPOOL.

974,139.

Specification of Letters Patent.

Patented Nov. 1, 1910.

Application filed July 28, 1909. Serial No. 510,072.

To all whom it may concern:

Be it known that we, JOHN C. HEBDEN and FREDERICK H. DANIELL, citizens of the United States, residing at Providence, in the 5 county of Providence and State of Rhode Island, and Franklin, in the county of Merrimack and State of New Hampshire, respectively, have invented certain new and useful Improvements in Jack-Spools, of 10 which the following is a specification.

Our invention is an improved jack-spool or dresser-spool for use in handling warp or filling yarns.

Our improvement provides a novel means 15 for supporting the yarn wound in multiple on a spool or beam in such form that the material may be removed from the spool without unwinding it to be dyed or similarly treated in the package; and may then 20 be returned to the spool after the dyeing in condition for delivering the ends in multiple without rewinding.

Our invention is fully set forth in the following specification, illustrated by the accompanying drawings, in which:

Figure 1 is a sectional view of the spool with the yarn mass represented by dot-and-dash lines; Fig. 2, an enlarged sectional view showing the arrangement for adjusting the heads along the barrel of the spool; Fig. 3, an enlarged end view showing the clamping device for securing the heads on the barrel.

There are two different methods now generally employed for handling yarn in preparing it for use in the loom either as warp or filling. With one method the yarn is wound into skeins to adapt it for dyeing, while with the other it is converted into 40 what is termed a "chain" before applying it to the dyeing process.

The process comprehending the dyeing of warp yarn in skein form has six distinct steps as follows: First, the yarn is wound 45 from the spinning bobbins into skeins; second, the yarn is dyed and dried in the skein; third, it is next wound from the skeins on to spools with a single end on each spool; fourth, from forty to sixty of the single 50 ends are wound from the spools on to a

larger spool called a jack-spool or dresser-spool; fifth, the multiple ends are taken from the jack-spool and wound on to the dresser where they are conditioned to prepare them for the weaving; sixth, from the 55 dresser the ends are wound on to the loom beam which is afterward transferred to the loom to deliver to the weaving. This same process is employed in preparing yarn for use as filling except that in the final steps 60 the yarn is wound from the jack-spool into filling bobbins by a machine called a "jack" or "bank" quiller instead of being dressed and wound on to the loom beam.

Where the chain dyeing system is used 65 the yarn is handled as follows: First, the yarn is converted from the spinning bobbins into the chain warp which is virtually a long untwisted rope of several hundred strands; second, the yarn is dyed and dried 70 in the chain; third, the chain is split and wound in multiple ends on to beams; fourth, the ends are wound from the beam in multiple on to the slasher beam; fifth, the multiple ends are delivered to the slasher to be 75 sized and dried; and sixth, from the slasher the yarn is wound on to the loom beam, if intended for use in the loom as warp. If the yarn is to be used for filling it is wound from the chain into quills or filling bobbins 80 to be used in the shuttles of the loom.

Heretofore, it has always been necessary to convert the yarn from the bobbins either into skein or chain form in order to dye it, and after the dyeing another rewinding 85 process is necessary to transfer the skeins or chains; as the case may be, on to spools so that the ends may be wound in multiple on to the jack-spool. Our invention provides for winding the yarn in multiple direct from the bobbin to the jack-spool and comprehends the dyeing or other similar treatment of the yarn in the form of long cylindrical packages adapted for use in delivering the yarn from the jack-spool to 90 the dresser.

In Fig. 1, A is the jack-spool comprising a barrel *a* and heads *b* and *c* adjustable along the barrel. The barrel *a* is preferably of hollow form and may be either cylindrical 100

or of angle shape as shown more particularly in Figs. 2 and 3. Surrounding the barrel is a longitudinally contractible tube B formed of a helical coil of wire, or other attenuated metal, extending the whole length of the barrel a between the heads b and c. The coil d is covered by a flexible sleeve e of fabric or other porous material, either knitted, netted, woven or braided in reticulated form.

Secured in the ends of the barrel a are two blocks f and g having central holes threaded to receive the threaded ends of the studs h and i which serve as trunnions for supporting the spool rotatively. The trunnions h and i are formed with shoulders j and k and two flanges or disks l and m are fitted to the smaller diameters of the trunnions and adapted to abut the shoulders j and k.

When the trunnions are screwed into the blocks f and g the flanges l and m are brought up tight against the ends of the barrel a and held securely between the blocks and the shoulders on the trunnions.

Fitted to the barrel a and adapted to slide along its length are the two heads b and c which are preferably formed of wood and protected by a thin sheathing of metal, represented by b'-c', covering the outer faces of the heads and spun over on the rims to prevent the wood from chipping off. The heads b and c are provided with a suitable number of buttons or fasteners n, n, etc., three being shown in Fig. 3, which are pivoted on rivets o, o, etc., and adapted to be turned to overlap the flanges l and m. The fasteners n, n, etc., bind on the rim of the flanges and hold the heads b and c close up against their faces.

By unscrewing the trunnions h and i the flanges l and m can be removed from the ends of the barrel a and this, provides for removing the heads b and c from the barrel. It is necessary that at least one of the heads be removable in order that the tube on which the yarn is supported may be taken from the barrel and applied to the apparatus used in the process of dyeing the yarn. After the yarn has been dyed on the tube it is replaced on the barrel and the heads b and c set up against the ends of the mass. The tube B is adapted to contract longitudinally so that the yarn may be compressed before applying the dyeing fluid, as hereafter more particularly described, and after subjection to the dyeing process the whole mass of yarn on the tube will be shortened somewhat as compared to its original length when first wound. When the tube B is again applied to the barrel a it will therefore be necessary to adjust the heads b and c in from the ends of the barrel to bring them against the ends of the package. To pro-

vide for this we make use of clamps C which are illustrated in Figs. 2 and 3. 85 These clamps consist of two parts p and p' having opposite openings p² and p³ shaped to fit the barrel a and clamped together on said barrel by means of the bolts q-q. Both portions of the clamp C are formed with a circular rim r of the same diameter as the flanges l and m so that the fasteners n, n, etc., which are adapted to bear on the flanges are likewise adapted to engage the rim r-r.

Fig. 2 shows one of the heads c moved in from the end of the barrel a and held by the clamp C which may be secured at any point along the length of the barrel a, see also Fig. 3. It will be understood that the clamps C are for use only in adjusting the 80 heads along the barrel and securing them thereto when the length of the yarn package is less than the full length of the barrel. They are not required when the yarn package 85 extends the whole length of the spool and the heads are fastened to the flanges l and m.

The operation of our device as used in handling yarns to prepare them for delivery to the warp beam or quiller is as follows: 90 The spool is first assembled as shown in Fig. 1 with the heads b and c secured against the flanges l and m at the ends of the barrel a and the contractible tube B supported on the barrel between the two heads. In this form the spool is applied to a suitable winding machine and the yarn wound thereon in multiple according to the number of ends required. In Fig. 1 we have illustrated the 95 yarn mass by dot-and-dash lines which represent forty ends wound side by side to a diameter equal to the diameter of the heads b and c and forming one long package composed of forty or more narrow cheese-like cops x-x, etc., abutting each other. After 105 the spool is filled with the yarn it is removed from the winding machine and one of the heads is taken off by unscrewing one of the trunnions h or i and removing the corresponding flange l or m. The barrel of the 110 spool is then withdrawn from the tube B, leaving a cylindrical mass of yarn supported by the tube which forms a pervious, contractible holder for the yarn. The yarn is then applied to a dyeing apparatus such, for 115 instance, as that shown and described in our patent application Serial No. 427,379, filed April 16th, 1908. With this apparatus the yarn package is placed between two heads or end flanges and the flanges are then 120 drawn together to contract the mass longitudinally to bring all of its portions to a uniform density. The dye-liquor or other fluid is then forced into the tube B and escapes through the foraminous walls of the 125 tube to penetrate the mass. As set forth in

the application above referred to, the compression of the yarn gives a uniform density to the mass so that all parts are dyed evenly and a much better result is secured than when the yarn is dyed in the skein or chain. After the yarn has been dyed and then thoroughly dried by forcing steam or hot air through the mass while the latter is held under compression the package is removed from the dyeing apparatus and transferred bodily to the jack-spool again. As before stated, the length of the package will be slightly less than its full length when first wound, owing to the compression of the mass during saturation, and when the tube B is applied to the barrel *a* it will be necessary to adjust the heads *b* and *c* in from the ends of the barrel to bring them against the ends of the package to protect the yarn and prevent its falling down on to the barrel. This is accomplished by unfastening the fasteners *n*, *n*, etc., from the end flanges *l* and *m* and applying the clamps C, C to the barrel *a* in proper position to hold the heads *b* and *c* against the ends of the package. When the clamps C, C are properly positioned the bolts *q*, *q* are tightened to bind the clamps on the barrel and the buttons or fasteners *n*, *n*, etc., are then swung around to engage the rims *r* of the clamps. The dyed and finished yarn is now in condition to be delivered direct from the jack-spool to the dresser and thence to the warp-beam, or from the jack-spool to the quiller to be wound into filling bobbins.

It will be seen that our invention provides for the elimination of two steps in the usual process now employed in preparing warp or filling yarns for delivery to the weaving. By the use of our device the operation of winding from the spinning bobbin into skeins or chains is obviated, and also the operation of rewinding from the skeins or chains on to single end spools is done away with. Further, the yarn can be handled much more economically in the dyeing or similar processes when contained in the relatively large packages as described than is possible when the yarn is in the form of skeins or chains. The handling of yarn in skein form is open to many objections, owing to the liability of the ends becoming snarled and tangled together or being lost in the loose coils which constitute the skein. There is always a considerable loss of time and waste of the yarn in transferring it from skeins to spools and the operation is extremely slow and difficult. There are these same objections, besides others, to handling yarn in chain warps. The long lengths of yarn often become tangled together and it requires great skill and care in winding the ends from the chain. The chains are usually

stretched out on the floor and take up considerable space during the winding operation which is very slow, as the ends must be watched very carefully and kept straight.

By the use of our new device we effect the saving of two operations in the handling of the yarn, eliminate a large percentage of the waste, and accomplish a much better result in the dyeing process. Besides providing for adjusting the heads of the spool to compensate for the compression of the yarn, our improvement also adapts the device to be used for different lengths of packages wound on the spool. In other words, any number of ends may be wound on the spool and the flanges adjusted the proper distance apart to accommodate the length of the winding.

We are aware that it is not new in the art to provide a spool or beam with heads adjustable lengthwise of the barrel and adapted to be clamped to the barrel by a two-part clamp-ring. Therefore, we do not claim this feature of our device broadly, but

What we do claim is:

1. In a spool the combination with a barrel *a*, of a longitudinally compressible, pervious tube B supported on the barrel and removable heads *b*—*c* adapted to be secured to the barrel.

2. In a spool the combination of a barrel, a longitudinally contractible, pervious tube supported on the barrel, heads adapted to slide along the barrel and means to secure the heads at different points on the barrel.

3. In a spool the combination of a barrel, a longitudinally contractible, pervious tube supported on the barrel and heads adjustable along the barrel.

4. In a jack-spool the combination of a barrel, a longitudinally contractible, pervious tube supported on the barrel, heads slidable on the barrel, means to secure the heads at the ends of the barrel, and separate means to secure the heads at points in from the ends of the barrel.

5. In a jack-spool the combination of a barrel, a longitudinally contractible, pervious tube supported on the barrel, flanges removably fastened to the ends of the barrel, heads adapted to be secured to the flanges, and clamps adapted to be clamped to the barrel and arranged to secure the heads at different points along the barrel.

6. In a jack-spool the combination of a barrel formed of angle iron, a longitudinally contractible, pervious tube supported on the barrel, blocks fastened in the ends of the barrel, trunnions screwed into the blocks and formed with shoulders, flanges held between the blocks and the shoulders on the trunnions, heads fitted to the barrel, and fasteners on the heads adapted to engage the flanges to secure the heads thereto.

- 4
7. In a jack-spool the combination of a barrel, a helically coiled wire supported on the barrel, a tubular, flexible, pervious covering surrounding the coils, and heads removably secured on the barrel.
  8. In a jack-spool the combination of a barrel, a longitudinally contractible, tubular, ribbed frame supported on the barrel, a flexible, pervious covering surrounding the

frame, and heads removably secured to the barrel.

In testimony whereof we affix our signatures in presence of two witnesses.

JOHN C. HEBDEN.
